UNITED STATES PATENT OFFICE.

RALPH P. TUTTLE, OF MORRISTOWN, NEW JERSEY, ASSIGNOR TO THE UNION SWITCH & SIGNAL COMPANY, OF SWISSVALE, PENNSYLVANIA, A CORPORATION OF PENNSYLVANIA.

RAILWAY SIGNALING DEVICE.

Application filed May 24, 1922. Serial No. 563,181.

This invention relates to railway signaling and particularly to an improvement in the well known track circuit used universally in automatic railway signaling.

5 The track circuit as commonly used at the present time in railway signaling consists generally of a source of difference of potential connected across the two rails of an insulated section of trackway at one point and a translating device connected across the rails of the same section at another point. The arrangement of the track circuit varies due to local conditions but the allowable variations are well within the skill of the 10 trained signal engineer and however varied comprise at least the elements specified.

At the present time and in the present state of the art, if it may be said of any one element of a signal system that it is more important than the remainder, it may be said 15 of the track circuit. It is a fact that the proper operation of all track circuit controlled signaling depends in the first instance upon the proper operation of the track circuit. It is the heart, so to speak, of the system.

When it was first proposed to connect a source of difference of potential across the rails of a section and operate a translating 20 device connected across the rails of the same section at a remote point it was, judged from the experience then available, an impossibility. It was tried, however, and found to operate, and operate so well that thousands 25 of miles of railway are now so equipped.

Originally the so called gravity cell was used as the source of difference of potential and it was found that two gravity cells connected in multiple with a relay of about 20 ohms resistance as a translating device with the average length of section gave the best results generally. Just why the four ohms relay was used rather than one of some other resistance, nobody seems to know, but the gravity cell was used probably because inexpensive and the one with which the type of man who would naturally be expected to experiment with track circuits was most familiar, namely, a man acquainted 45 with the telegraph art. The gravity cell, however, has a valuable characteristic in that it has a high internal resistance and consequently can withstand the drain caused by a train standing on the section for a

long time. Furthermore, the electro-motive force is of such value that excessive leakage from rail to rail throughout the section does not take place, when a fairly reasonable track insulation resistance is maintained.

60 Experience with the track circuit constructed as described, for about fifty years, has resulted in generally retaining the four ohm relay as a translating device, leaving out of consideration alternating current track circuits, but in a more or less general adoption of the caustic soda primary battery of the Lalande type for the source of electro-motive force. This type of battery, all things considered, is superior to the gravity, 65 both in maintenance cost and perfection of operation of the track circuit. Its introduction was distinctly favorable to better operation of track circuits.

The caustic soda battery has, however, 70 characteristics which necessitate slightly different treatment. For instance, a resistance must be inserted in series with it to prevent the exhaustion of the battery when a train stands on the section for a long time. 75 This resistance must, of course, be such that the proper difference of potential is impressed across the rails so that the relay will operate properly when no train is on the section.

80 It is well known that the two rails of a railway track are commonly laid on wooden cross ties which generally rest on rock, gravel or dirt ballast and that the insulation resistance between the rails is comparatively low even in dry weather, but when rain falls on the trackway or snow falls thereon, and melts, the insulation resistance is considerably reduced. So under 85 any condition the difference of potential between the rails must be comparatively low else an undue waste of energy takes place through all of the leakage paths between the rails, between the point where the difference of potential is impressed and the translating device is positioned. This is a serious matter where batteries are used to supply the E. M. F. Of course by cutting down the difference of potential as much as possible waste is prevented and the shunting 90 characteristics of the track circuit are improved, that is, a higher resistance shunt across the rails will deenergize the relay,

but if the margin of excess difference of potential is small, the difficulty is present that the leakage may become so great that the proper difference of potential will not exist across the relay terminals consequently even with no train on the section the relay will be deenergized and the signal controlled thereby will be at danger. This, of course, is a failure on the safe side, but 10 delays traffic and cannot be endured, consequently, the resistance must be such that the relay will be properly energized even under the worst conditions, that is with the lowest ballast resistance, which is probably 15 when the trackway is thoroughly wet. If this is done, then in dry weather, with a higher ballast resistance an excessive difference of potential exists across the relay terminals resulting in waste, and also shunting 20 characteristics of the track circuit are not so good, that is, it requires a lower resistance across the track rails to shunt the relay. This is very undesirable, because the failure of a train to properly shunt the 25 track circuit leaves the signal controlled thereby at safety when it should be at danger, a condition which must not be allowed to exist.

There are then two variable conditions to 30 be met necessitating high difference of potential with low track insulation and low difference of potential with high track insulation, in order to get economy and proper shunting characteristics under all 35 conditions of track ballast. The result is that in order to provide for both it is now common to insert an adjustable resistance in circuit with the battery and adjust it as frequently as possible in accordance with 40 weather conditions, but due to the fact that most people take the easiest way the ultimate result is generally that it is adjusted to take care of wet ballast and not altered when the ballast becomes dry, consequently 45 during dry weather the output from the battery is excessive resulting in waste and the shunting characteristics of the track circuit are not as desired.

The difficulties pointed out are present in 50 track circuits because there exists at the present time no means for automatically varying the value of the inserted resistance due to change in ballast resistance due to weather conditions.

55 The principal object of applicant's invention is to relieve from the difficulties hereinbefore pointed out by providing a resistance or resistor which will be automatically and properly affected to compensate for the 60 changes in ballast resistance arising from weather conditions such as wet track, due to rain, melted snow or ice, or dry track due to prolonged dry weather, in such a manner that undue waste of battery will be prevented and proper shunting characteristics

of the track circuit will be maintained, to the end that the old and well known and thoroughly tried out track circuit will be brought to a state of efficiency comparable with present advanced engineering practice 70 and the safety of railway travel will be enhanced in accordance with the present advanced standards of railway practice and the plea of the public for the conservation of human life and materials. 75

Other objects and advantages will appear as the description of the particular physical embodiment selected to illustrate the invention progresses, and the novel features of the invention will be particularly pointed out in the appended claims. 80

In describing the invention in detail, and the particular physical embodiment selected to illustrate the invention, reference is had to the accompanying drawings, wherein I 85 have illustrated a particular preferred physical embodiment of my invention and desirable modifications thereof, and wherein like characters of reference designate corresponding parts throughout the several 90 views, and in which:

Figure 1 is a vertical sectional view of a device embodying my invention on the plane indicated by the line I—I of Fig. 2, viewed in the direction of the arrows at the 95 end of the line;

Fig. 2 is a top plan view of a device embodying my invention; Fig. 3, is a view similar to Fig. 1, of a modified form of device embodying my invention; Fig. 4, is a fragmentary top plan view of the device as illustrated by Fig. 3; Fig. 5, is a fragmentary side view of a coil shown in Fig. 1, illustrating an acceptable method of winding; Fig. 6, is a horizontal cross sectional view 100 on the plane indicated by line VI—VI of Fig. 3, viewed in the direction of the arrows at the ends of the line; Fig. 7, is a fragmentary side view of a coil illustrated in Fig. 3 showing an acceptable method of winding 105 and illustrating fluid conducting members protruding therefrom; Fig. 8, is a fragmentary horizontal cross sectional view of the coil illustrated in Fig. 3; Fig. 9, illustrates an application of my invention to its combination in a direct current track circuit; Figs. 10 to 14 inclusive illustrate the application of my device in combination with variously arranged alternating current track 110 circuits; Fig. 15, illustrates a device used in my invention buried in the ballast of a trackway; Fig. 16, illustrates a device used in my invention resting on a tie of a trackway. Fig. 17 illustrates a combination of two possible positions of location for a device employed in my invention. 115

120 Referring to Fig. 1, there is designated by numeral 1, a coil which is preferably wound "honeycomb", as illustrated by Fig. 5, in which 3, 4 and 5 designate portions of 130

the same continuous wire, preferably what is known as, resistance wire, that is having a resistance much greater per unit length than such wire as ordinary copper wire and 5 being covered with an insulating material to prevent the several layers from contacting conductively. This insulation material might preferably well be plain cotton or silk, it being merely necessary that the insulation is so pervious to moisture or water that when moisture or water is present the insulation material will become saturated and a path of comparatively low resistance be formed from layer to layer and from one 10 portion of the wire to an adjacent portion.

The coil 1 is intended to be inserted in series in a track circuit such as is shown by Fig. 9. In Fig. 9, 6 and 7 designate two track rails formed into an insulated section 20 by insulating joints 8. A battery 9, as illustrative of a source of a difference of potential is provided, one terminal of the battery being connected by conductor 10 to track rail 7 adjacent the insulating joint 8 25 as is customary. The other terminal of the battery 9 is connected by conductor 11 to the terminal wire 12, as shown in Fig. 1, of the resistance coil 1. The other terminal 30 of the resistance coil is connected by conductor 14 to the other track rail 6, adjacent the joint 8. At the other end of the section the relay 15 is connected to the rails 6 and 7 adjacent the insulating joints 8, situated at that place by conductors 16 and 17, respectively. This construction is that of the ordinary and well known track circuit, and the relay 15, by its armature 18, is intended to control in the well known manner any desired and proper signaling device, with this 40 exception, however, that resistance coil 1 is inserted in series in the circuit.

In the construction illustrated by Fig. 9 the resistance of coil 1 would be such that when dry, the difference of potential impressed across the track rails would be proper for the insulation resistance between rails 6 and 7 which would be present when the ties 19 and ballast 20 were in ordinary condition, which is assumed to be substantially 50 dry. Of course, although I have assumed a fixed and unvarying resistance for coil 1, when dry, and consequently such as would be especially adapted, taking into account the length of track circuit and local condition for the particular track circuit to which it is applied, nevertheless I do not mean to exclude by such statement the use of a coil of adjustable resistance value when dry, as that is a variation well within the skill of 60 the art.

It is contemplated that coil 1 will be exposed as nearly as possible to the same weather conditions as the trackway, so I have shown coil 1 in Fig. 9 as directly exposed without covering of any kind, con-

sequently, when moisture is precipitated either as dew, rain or snow, the coil 1 will equally with the trackway be affected by such precipitation. The precipitation of dew or rain and also of snow after being 70 melted causes the insulation resistance between the track rails to lower due to the saturation more or less complete of the ties and ballast. Under such conditions the leakage from rail to rail will be so heavy 75 that if resistance coil 1 is a proper resistance for dry trackway, it will be too great a resistance for the trackway when saturated with moisture. It will impress too small a difference of potential across the 80 rails 6 and 7. By applicant's invention the difficulty is remedied automatically, because the coil 1 being subjected to the same weather conditions as the trackway, when that becomes saturated with moisture the 85 coil 1 also becomes saturated with moisture, the resistance from layer to layer and from one portion of the wire to another becomes less and consequently the total resistance of the coil is less and as a result the battery 90 9 operating through less resistance is able to impress a greater difference of potential across the rails 6 and 7, thereby compensating for the lower insulation resistance between rails and the greater leakage. Of 95 course the reverse of the above described change takes place when the weather changes to dry, because then as the trackway becomes less moist, the coil 1 becomes less moist and its total resistance increases 100 so that the battery 9 is able to impress only a lesser difference of potential across the rails 6 and 7.

I contemplate the use of my automatically variable resistance coil 1 not only with 105 what are known as direct current track circuits, such as is illustrated by Fig. 9, but also with what are known as alternating current track circuits, such as are illustrated conventionally by Figs. 10 to 14, inclusive. I further desire to state that although I have in all cases illustrated my automatically variable resistance coil 1 in connection with what are known in the art as end fed track circuits, I desire to have 110 it understood, that the showing is merely illustrative and I do not desire to be limited to such use or to exclude other well known forms of track circuits as included within the domain of my improvements as full 115 equivalents of the end fed track section, such for instance as the center fed track section.

In Fig. 10, I have shown two track rails 6 and 7, line wires 21 and 22 carrying alternating current, a transformer 23 feeding the track rails through my coil 1 in series therewith and at a remote point in the section the so called, well known single element, translating device or relay of the 120 125 130

vane type, which of course is merely illustrative of a translating device receiving all of the energy for operation from the trackway, and although such a relay cannot be 5 operatively affected by direct current nevertheless I do not desire to be understood as excluding the use of the simple and well known translating device or relay operable as well by direct current as by alternating 10 current.

In Figs. 11, 12, 13 and 14, I have illustrated the two track rails 6 and 7, fed at one location, by alternating current from line wires 21 and 22 carrying alternating 15 current, through transformers 23 and at a remote point in the section a two element translating device or relay, shown as of the squirrel type of alternating current motor having two windings, one 24 fed from the 20 track, the other 25, fed through a transformer 26 connected across the line wires 21 and 22, it being understood that the showing is merely diagrammatic and conventional, the devices being all well known and 25 commonly used and the drawings being intended to illustrate merely the well known and used devices and to show the connections as commonly used, the whole object of the illustrations being to introduce in well 30 known connections applicant's automatically variable resistance coil 1.

The difference between the several Figs. 11 to 14 inclusive resides in the method of combining applicant's automatically variable resistance coil 1 with the track feed. In all of the figures the coil 1 is shown as 35 in a series circuit with transformer 23, and is shown as being substantially pure ohmic resistance, that is as having substantially no 40 reactance.

It is sometimes quite important when two element relays having two windings are employed to have the proper and best phase relations between the currents in the two 45 windings. This proper and best phase relation is obtained by the proper use of resistance and reactance or impedance. In Fig. 11 I have merely shown coil 1 in series with the transformer 23. In Fig. 12, I have 50 shown an impedance in multiple with coil 1. This raises the power factor of the circuit upon an increased current flow, that is when coil 1 is wet, which is under certain conditions desirable. In Fig. 13, I have shown, 55 the impedance 27 as in series with the coil 1. This arrangement lowers the power factor of the circuit upon an increased current flow, that is when coil 1 is wet, which is under certain conditions desirable. In 60 Fig. 14, I have shown an ohmic resistance 28 in multiple with coil 1 and an impedance 27 in series with coil 1. This arrangement gives another often desired result, in that it normally gives a high power factor, that

is under dry conditions, but when coil 1 is 65 wet it gives a low power factor.

The illustration Figs. 1 to 14 inclusive are, therefore, illustrative of the fact that applicant's coil 1 may be combined with an alternating track feed in connection with 70 various desired arrangements designed to have the proper effect upon the translating device or relay to suit the manifold differences of local conditions.

In order to obtain the desired result by 75 the use of applicant's exposed coil 1, it is readily understood that the coil 1 should be exposed in such a way as to reflect, at all times, accurately the exact conditions of the trackway as regards its state of moisture. This result may be obtained by various positioning of the coil 1. It may for instance be simply exposed as shown in Fig. 9, it may be buried in the trackway as shown in Fig. 15, a suitable or proper distance below the 80 top of the ties or it may be positioned on top of the ties as shown in Fig. 16. The most advantageous arrangement and positioning of the coil 1 at the present time seems to be, all facts considered, supported 85 on a structure beside the trackway and in the drawings applicant has illustrated such positioning.

In Fig. 1, a fragment of a trackway structure is designated by 29. By this structure, 90 by bolts 30 and 31, is supported a bracket 32, including spaced diverging arms 33 and 34 between which is positioned an inverted cone shaped precipitation receiver 35, having the larger end or opening facing upwardly. The upper opening is provided with an adjustable shield held preferably to receiver 35, by any desired proper and suitable means, as by screw 37, passing through an ear 38 on the shield into a 100 threaded lug 39 on the receiver, all as best shown in Fig. 2. By reason of this form of connection the shield 36 may be oscillated upon screw 37 as a pivot and more or less of the upper opening of the receiver exposed so that the proper quantity of atmospheric precipitation may be received in the 105 receiver.

To the underside of the receiver which is 110 preferably made of sheet metal is attached preferably by bolts as 40, a hollow cylindrical body 41, having an open upper end and a preferably conical sloping lower end terminating in an orifice of suitable size 42.

Within the cylindrical hollow body 41, is 115 a coil supporting and fluid distributing hanger 43, circular in horizontal cross section, formed for a portion of its lower length as an annulus, and formed in the upper portion as a cone. The body 43 is attached preferably to the underside of receiver 35, preferably by hangers 44, preferably secured at the upper ends by rivets 120 125

as 45 to receiver 35, and preferably secured to the hollow body 43 by rivets as 46. The lower edge of the body 43, is preferably turned so as to form a flange 47, so as to support coil 1, and the terminals 12 and 13 of coil 1 are conveniently connected to metallic binding posts 48 and 49, passing through the wall of cylindrical body 41 and suitably insulated therefrom, by insulation, 10 as 50 and 51.

The atmospheric precipitation received by receiver 35 passes through screen 52 and runs out of the open end 53 of the receiver, falling upon the conical surface of 43 and 15 being thereby distributed over the entire surface whence it flows down to coil 1 and wets the entire upper surface of the coil 1, then flows through coil 1, and drops upon the conical surface of the bottom of cylindrical body 41, and then flows to the orifice 42 and away from the apparatus.

The shield 36, by its adjusted positions governs the total amount of precipitation received by receiver 35, but it also is desirable to regulate the rapidity of flow through orifice 53. In order to do this applicant preferably provides an adjustable closure 54, for the orifice. This closure includes a head 55 formed to fit water tight into the lower 30 constricted portion of the receiver and is formed with a thread engaging a projecting threaded lug 56 attached by any suitable or appropriate means to the inside surface of the receiver preferably and preferably 35 attached by spot welding. The closure 54 is further provided with a suitable handle 57 so that head 55 may be advanced into and retracted from the orifice 53, and, consequently, by the size of the free opening left 40 after adjustment, the rapidity of flow of fluid through orifice 53 will be regulated.

The screen 52 not only prevents undesirably large particles which may enter receiver 35 from passing to coil 1, but also 45 acts as a support for snow, which upon melting passes through the screen as water.

Another desirable form of apparatus for exposing coil 1 to weather conditions comparable with those to which the trackway is 50 exposed is shown by Figs. 3, 4, 6, 7, and 8.

Figure 3, illustrates a trackway structure 29 and bolts 30 and 31, attaching bracket 32 to support 29, and the bracket 32 is formed just as is the bracket shown in Fig. 55 1, and supports in the same manner an inserted cone shaped receiver 58, having a shield 59, constructed and arranged and connected to receiver 58, just as shield 36, in Fig. 1 is constructed, arranged and connected to 60 receiver 35, and the shield performs the same functions as shield 36.

Receiver 58 is attached in any suitable appropriate or desired manner, as by welding to a threaded annular body 60, formed 5 with an internal thread 61, and to receiver 58

is attached the hollow cylindrical body 41, identical with body 41 illustrated in Fig. 1.

A core 62 is provided, preferably hollow, closed at its upper end and formed with a flange 63 at its lower end to support coil 64. 70

Coil 64 is wound "honeycomb" preferably, as shown by Fig. 7, and between each two layers, a material 65, preferably highly absorbent such as ordinary round lamp wicking is placed, spaced suitable distances apart 75 and protruding from the upper surface of the coil, as shown by Fig. 7. This wicking as shown by Fig. 3 is carried to a height about even with the top of core 62 and in order to keep it suitably in position it is 80 preferably bound with wire 66, wound helically about it so as to virtually form a screw thread.

In order to keep the wicking and wire in place a double threaded annulus 67 is provided, threaded internally and externally. The internal thread corresponds with the helically wound wire 66 and the external thread corresponds with thread 61, so that the annulus may be screwed into position 90 as shown in Fig. 3. After being screwed into position the annulus is prevented from further movement by pin 68, driven through previously formed openings in 60, 62 and 67. 95

In order to further regulate the quantity of fluid which will pass down through the wicking to the coil 64, and then out at orifice 42, I have further provided an overflow cock 69. This cock, when open, regulates the height to which fluid will rise in 100 receiver 58, as is obvious and so regulates the total quantity of fluid which will pass down through the coil 64.

In the form of the device illustrated by Fig. 3, snow will be received and retained by the receiver 58 until it melts and then the water thereby produced will pass down through the wicking 65.

Core 62 may be formed of any appropriate material preferably copper, brass, or iron. 110 If formed of iron the coil 64 will act not only as a resistance but will also act as an impedance and so change the power factor of the circuit in which it is included in accordance with its condition as wet or dry. 115

Throughout the description I have described and in the drawings illustrated a honeycomb wound annular resistance coil, but I of course do not mean to limit my invention to the particular form of coil, or in fact to the use of a coil because fundamentally considered, my resistance in principle may merely include the exposure of two parts of a resistance member to the action of atmospheric precipitation whereby the intermediate portion is shunted electrically and because I do not mean to exclude other ways of forming a resistance unit which are usable with my invention, or even straight parallel bars or sheets held closely adjacent one an- 120 125 130

other as the resistance unit, where the resistance between the bars or sheets may be decreased by the presence of moisture and increased upon the absence of moisture, or even a single bar of suitable length and material buried in the trackway and connected in series with the source of E. M. F.

Although I have described my automatically variable resistance as being connected in series with a track circuit and located either in an exposed position, in the ballast, on a tie or supported by a trackway structure, nevertheless, I desire to have it understood that combinations of these various positions may be used, such for instance, as the combination shown in Fig. 17. In Fig. 17, I have shown one coil 1 as resting on a tie and in series with the battery 9, and another coil 1, buried in the ballast and in series with battery 9, but in multiple with the coil 1 resting on the tie. My idea is that in dry weather the combined multiple circuit resistance will be regulated so as to be proper for the particular track circuit in which it is used. When a light shower comes, then the coil 1 on the tie will be immediately affected to allow an increased current flow, even before the coil 1, buried in the ballast is affected. If, however, the shower continues and the trackway throughout become thoroughly wet, then the insulation resistance between rails being further reduced and a greater impressed difference of potential across the rails being required, it is automatically supplied by the reduced resistance of the coil 1 buried in the ballast which when the trackway is subjected to a saturating shower also becomes saturated.

Although I have particularly described the construction of one physical embodiment of my invention and desirable modification thereof, and explained the operation and principle thereof, nevertheless, I desire to have it understood that the forms selected are merely illustrative, but do not exhaust the possible physical embodiments of the idea of means underlying my invention.

What I claim as new and desire to secure by Letters Patent of the United States, is:

50 1. In a railway track circuit, in combination: a translating device connected across the rails at one location and means governed by the presence or absence of water in contact therewith for automatically impressing varying differences of potential across the rails at another location in such manner that when the track insulation resistance increases, the difference of potential decreases, and vice versa.

60 2. In a railway track circuit, in combination: rails; a source of a difference of potential connected across the rails at one location; a translating device connected across the rails at another location and means governed by the presence or absence of water

in contact therewith for varying the impressed difference of potential.

3. In a railway track circuit, in combination: rails; a source of a difference of potential connected across the rails at one location; a translating device connected across the rails at another location and means governed by atmospheric condensation in contact therewith for automatically varying the impressed difference of potential. 75

4. In a railway track circuit, in combination: a source of a difference of potential connected across the rails at one location; a translating device connected across the rails at another location and means governed by atmospheric precipitation in contact therewith for varying the impressed difference of potential. 80

5. In a railway track circuit, in combination: a source of difference of potential connected across the rails at one location; a translating device connected across the rails at another location and means governed by precipitated moisture in contact therewith for varying the impressed difference of potential. 85 90

6. In a track circuit, in combination: rails; a source of substantially constant E. M. F. connected across the rails and a resistance in series therewith and automatically variable by the amount of water in contact therewith to decrease upon a decrease of track insulation resistance and increase upon an increase of track insulation resistance, and means to utilize the varying difference of potential thereby created. 100

7. In a track circuit, in combination: rails; a source of E. M. F. connected across the rails and means in series with the source of E. M. F. variable in resistance in accordance with the amount of water in contact therewith to decrease upon a decrease in track insulation resistance and increase upon an increase of track insulation resistance and means to utilize the difference of potential created. 105 110

8. In a track circuit, in combination: rails; a source of E. M. F. connected across the rails and means in series with the source of E. M. F. varied in resistance by the presence or absence of water in contact therewith. 115

9. In a track circuit, in combination: rails; a source of E. M. F. connected across the rails and means interposed in series with the source of E. M. F. constructed to be varied in resistance by the presence in contact therewith of precipitated atmospheric moisture. 120

10. The method of operating track circuits which consists in automatically regulating predeterminedly the impressed difference of potential in accordance with track circuit requirements when unoccupied. 125

11. The method of supplying energy to a 130

- track circuit which consists in impressing one difference of potential across the rails during one condition of the weather and automatically impressing a predeterminate 5 different difference of potential across the rails during another condition of the weather.
12. The method of feeding energy to a track circuit which consists in inserting a 10 resistance in series with the energy, and exposing the resistance to precipitated atmospheric moisture for the purpose of varying the impressed difference of potential.
13. The method of feeding energy to a 15 track circuit which consists in automatically regulating predeterminately the impressed difference of potential in accordance with track circuit requirements as governed by weather conditions.
- 20 14. The method of feeding energy to a track circuit which consists in automatically regulating predeterminately the impressed difference of potential by the action of precipitated atmospheric moisture.
- 25 15. The method of automatically regulating predeterminately the difference of potential impressed on the two rails of a track circuit which consists in varying the total 30 resistance of a resistance inserted in series with the source of difference of potential by the action of precipitated atmospheric moisture.
- 35 16. In a railway track circuit, in combination: rails; a source of a difference of potential connected across the rails; a resistance wire connected in series with the source of difference of potential and exposed to weather conditions whereby precipitated atmospheric moisture may shunt a portion or 40 all of the resistance and means for utilizing the varying impressed different differences of potential.
- 45 17. As an article of manufacture, a resistance wire having terminals constructed to be shunted by the presence of precipitated atmospheric moisture.
- 50 18. As an impressed difference of potential regulator for a track circuit, a resistance wire exposed to atmospheric precipitation and arranged to be shunted predeterminately thereby.
- 55 19. As an automatically variable resistance for a track circuit, the combination with a coil of resistance wire of means for receiving and conducting atmospheric precipitation in the form of water thereto.
- 60 20. As an automatically variable resistance for a track circuit, the combination with a coil of insulated resistance wire of fluid absorbing and conducting material inserted into the body of the coil and an atmospheric precipitation receiver and container into which the said material operatively extends.
21. As an article of manufacture, an automatically variable resistance for a track circuit comprising a coil of insulated resistance wire, a fluid absorbing and conducting material inserted into the body of the coil and protruding therefrom in position to absorb precipitated atmospheric moisture. 65
22. In an automatic resistance for a track circuit, in combination; a coil of resistance wire having terminals; a hollow body formed with an orifice at its lower end surrounding the coil; binding posts passing through the wall of the hollow body, the said terminals being connected to the said binding posts inside of the hollow body and means for receiving and conducting precipitated atmospheric moisture to the said coil. 75
23. In an automatic resistance, in combination: a receiver formed with an open top and terminating at the bottom in a threaded orifice; an annulus formed with an internal and an external thread screwed in said orifice; a coil of resistance wire positioned below the annulus; water absorbing and conducting material extending into the body of said coil and extending upwardly to the bottom of said receiver and the top of said annulus; wire wound helically about said material and fitting into the internal threads of said annulus; a core about which the coil and said material are positioned and a pin passing through the receiver, the annulus and the core whereby all are held in definite position; means for making connections to the coil, and a flange formed on the lower end of said core for supporting the coil, substantially as and for the purpose described. 85 90 95
24. In a railway track circuit, in combination: a translating device connected across the rails at one location; means for supplying alternating current thereto and means including means governed by the presence or absence of water in contact therewith for automatically varying the power factor of the alternating current. 100 105 110
25. In a railway track circuit, in combination: rails; a source of alternating current connected across said rails; means for utilizing the alternating current and means governed by the presence or absence of water in contact therewith for varying the power factor of the current. 115
26. In a railway track circuit, in combination: rails; a source of alternating difference of potential connected across the rails; means to utilize the said difference of potential and means governed by the presence or absence of water in contact therewith for varying the impressed difference of potential and the power factor of the current. 120 125
27. In a railway track circuit, in combination, a source of alternating difference of potential connected across the rails; means

- for utilizing said difference of potential and means governed by the presence or absence of water in contact therewith for varying the power factor of the current.
- 5 28. In a railway track circuit, in combination: rails; a source of alternating current connected across the rails at one location; a translating device at another location controlled by said current and means governed by the presence or absence of moisture in contact therewith for varying a power factor of the current.
- 10 29. In a railway track circuit, in combination: rails; a source of alternating current connected across the rails at one location; a translating device at another location controlled by said current and means governed by the presence or absence of moisture in contact therewith for varying the amplitude 20 of the current.
- 15 30. In a railway track circuit, the combination of a source of alternating current, a translating device controlled by current from said source and means governed by atmospheric moisture in contact therewith for varying the amplitude and the power factor of the current.
- 20 31. In a railway track circuit, the combination of a source of alternating current, a translating device controlled by current from said source and means governed by atmospheric moisture in contact therewith for varying the amplitude of the current.
- 25 32. In a railway track circuit, the combination of a source of alternating current, a translating device controlled by current from said source and means governed by atmospheric moisture in contact therewith for varying the power factor of the current.
- 30 33. In combination: means for supplying a difference of potential, means for utilizing the difference of potential supplied and an impedance for limiting the current governed by atmospheric precipitation in contact therewith whereby the impedance thereof is varied.
- 35 34. In a railway track circuit, in combination: rails; a source of alternating current connected across the rails at one location; a translating device partly controlled by power from said source and means governed by atmospheric precipitation in contact therewith for maintaining a substantially uniform difference of potential and power factor at the said translating device.
- 40 35. In a railway track circuit, in combination: rails; a source of alternating current connected across the rails at one location; a translating device partly controlled by power from said source and means governed by atmospheric precipitation in contact therewith for maintaining a substantially uniform power factor at the said translating device.
- 45 36. In a railway track circuit, in combination: rails; a source of alternating current connected across the rails at one location; a translating device partly controlled by power from said source and means governed by atmospheric precipitation in contact therewith for maintaining a substantially uniform difference of potential at the said translating device.

RALPH P. TUTTLE.
